UNITED STATES PATENT OFFICE.

WILLIAM E. CLARK, OF MOLINE, ILLINOIS.

DISK-SHARPENER.

SPECIFICATION forming part of Letters Patent No. 675,816, dated June 4, 1901.

Application filed May 25, 1900. Serial No. 17,990. (No model.)

To all whom it may concern:

Be it known that I, WILLIAM E. CLARK, a citizen of the United States, residing at Moline, in the county of Rock Island and State 5 of Illinois, have invented a new and useful Disk-Sharpener, of which the following is a specification.

This invention relates to disk-sharpeners in general, and more particularly to that class 10 adapted for the sharpening of the disks of farm implements by hand-power, one object of the invention being to provide a simple structure comprising a supporting-bracket which may be secured to any suitable portion 15 of a barn or to a suitably-located post to hold it rigid, and which comprises means for readily applying and removing a disk and for holding and operating a cutter to cause it to travel around the disk, and thus cut an even 20 chip.

A further object of the invention is to provide a construction by means of which preliminary chips may be first taken at different angles, preparatory to the taking of a final 25 chip to finish the disk.

In the drawings forming a portion of this specification, and in which similar numerals of reference designate like and corresponding parts in the several views, Figure 1 is a perspective view showing the complete cutter attached to a post and illustrating the position of a disk during the sharpening operation. Fig. 2 is a transverse section taken through the supporting-bracket and the 30 ratchet-carrying arm and showing the disk-support and the cutting mechanism in elevation. Fig. 3 is a section on lines 3 3 of Fig. 2. Fig. 4 is a section on line 4 4 of Fig. 2. Fig. 5 is a section on line 5 5 of Fig. 2, with the 35 operating-lever omitted and illustrating the clamp and carrier by means of which the cutting-tool is supported, the clamping-bolt being shown in elevation. Fig. 6 is a detail perspective view showing the supporting-bracket and the protruding end of the pawl carried thereby. Fig. 7 is a perspective view showing the uppermost element of the 40 combined clamp and tool-carrier. Fig. 8 is a perspective view showing the upper jaw of the clamp of the tool-carrier. Fig. 9 is a perspective view showing the lower jaw of the clamp of the tool-carrier. Fig. 10 is a perspective

view showing the connecting-link by means of which the operating-lever is connected with the supporting-bracket and illustrating 55 the friction-roller carried thereby. Fig. 11 is a perspective view showing the tool employed by me.

Referring now to the drawings, the present invention comprises a supporting-bracket 60 including an arched base 15, at one end of which arch is a foot 16, having an opening 17 for the passage of a bolt by means of which the bracket is held upon a suitable support. From the opposite side of the base of the 65 bracket extends an arm 18, at the end of which is a forwardly-extending casing 19, in which is disposed a pawl 20 for a purpose which will be presently explained, and which pawl is held normally with its outer beveled 70 end 21 projected exteriorly of the casing by means of a helical spring 22, the ends of which encircle pins 23 and 24, carried by the base of the pawl and the base of the casing, respectively. This arm 18 may be provided 75 with openings for the reception of further securing-bolts.

Carried by the arch-shaped base 15 is a bearing-sleeve 25, which extends forwardly and parallel with the casing 19, and connecting this sleeve 25 and the adjacent face of the casing is a strengthening-rib 26, it being understood that all parts of the structure described, with the exception of the pawl and its spring, are cast or otherwise formed integral.

A carrier for the disk to be sharpened or a support therefor consists of a wheel 27, comprising a hub 28, spokes 29, and a rim 30, the hub being extended axially, as shown in Fig. 90 3, so as to project at one side of the wheel, and this projecting portion of the hub is tapered to fit within the bearing-sleeve 25. The extended portion 28 of the hub of the wheel has a lesser diameter than that portion of the 95 hub lying within the inclosure of the rim, resulting in the formation of a shoulder 31, which lies against the outer end of the sleeve 25. The outer face of the rim 30 of the wheel—that is, the face opposite to the hub extension—is beveled to the periphery of the rim, as shown at 32, the object of this bevel being to more snugly receive the face of the concaved side of a disk, (shown at 33,) and

which disk is adjusted to the supporting-wheel in such a manner that it will project beyond the periphery of said wheel. The disk is held in this position by means of a bolt 34, which is passed outwardly through the hub 28 and through the central perforation of the disk, a washer 35 being disposed between the head of the bolt and the adjacent ends of the sleeve 25 and hub 28. A frust-conical centering-block 36 is disposed upon the bolt 34, with its diminished end passed inwardly through the central opening of the disk, the centering-block 36 being drawn to this position by means of a nut 37 upon the outer threaded end of the bolt 34, and which engages directly with a washer 38, which it forces against the centering-block. By this means the disk is brought to lie concentric with its supporting-wheel and is held firmly in this position.

Upon the sleeve 25 is a peripheral flange 39, between which and the shoulder 31 is disposed a ring 40, which fits snugly upon the sleeve and between the flange and shoulder, this sleeve having a radially-disposed and perforated lug 41, to which the cutting mechanism is attached. The cutting mechanism comprises an operating-lever 45, to one end of which is bolted a bracket 46, comprising parallel ears 47, having perforations, and between these ears is disposed a link 48, which is pivotally connected therewith by means of a bolt 49, passed through the perforations in the ears and an alining perforation in the links. The link projects at both ends beyond the ears 47, and one of these projecting ends is perforated, as shown at 50 in Fig. 10, for the reception of a pivot-bolt 51, which is passed through the perforation 50 and the perforation of the lug 41, this link thus acting to connect the lever 45 movably with the supporting-bracket. The perforated end of the link 48 projects beyond the end of the lever 45, while the opposite end extends a slight distance along the face of the lever in an opposite direction and is provided at its extremity with a stub-shaft 52, upon which is mounted a friction-roller 53, held in place by means of a key 54 or in any other suitable manner. This friction-roller 53 is disposed to lie beyond the periphery of the supporting-wheel 30 and in a position to engage the surface of the disk during the cutting operation.

The cutting-tool is adjustably mounted upon the lever 45 through the medium of a carrier comprising three principal elements, of which two form clamping-jaws adapted to grip the lever 45, while the third is adjustably mounted and receives the cutting-tool directly. In the drawings this carrier is shown as comprising a lower jaw including a central portion 55, having a major upturned end 56 and a minor upturned end 57, between which ends and upon the upper face of the body portion are formed lugs 58 and 59, intermediate which is a squared perforation 60 for the reception of a clamping-bolt in a man-

ner to be presently described. The upper edge of the major upturned end 56 is tapered, as shown at 61, to enter the recessed edge of the major downturned end 62 of the body portion 63 of the upper jaw of the clamp of the carrier, this upper jaw also having a minor downturned end 64, which when the ends 56 and 62 are in engagement lie one above the other. Upon the lower face of the upper jaw are formed lugs 65, which lie at a distance from the adjacent face of the downturned end 64 equal to the distance between the end 57 of the lower jaw and the lugs 58 and 59, this separation being equal to the width of the lever 45, which is adapted to be received in these resultant recesses, as illustrated in Fig. 1. A perforation 66 is formed in the body portion of the upper jaw to align with the perforation 60, and through these perforations is passed upwardly a clamping-bolt 67, the squared portion of which adjacent the head fits the perforation 60 to prevent the bolt from rotating.

The tool-receiving element of the carrier has a circular flange 69 upon its lower face, which lies against the inner face of a similar flange 70 upon the upper end of the uppermost jaw, to permit rotatable adjustment of this tool-holding member without displacement, the tool-holding member having a central perforation 71, through which the bolt 67 is passed, said bolt having a clamping-nut 73 upon its upper end, which engages the tool-holding member and by forcing it downwardly upon the upper jaw holds it firmly thereagainst and at the same time clamps the jaws upon the operating-lever 45 in a manner which will be understood.

The tool-carrying member of the carrier is provided with a casing 75 at one side, which has a squared passage therethrough, and this passage is adapted to receive a correspondingly-formed tool 76 and hold it in a plane parallel with the upper face of the operating-lever 45, the tool being held in its proper adjusted position by means of a set-screw 77 engaging the threads of the perforation in the upper side of the casing and adapted to impinge the adjacent face of the tool.

As illustrated in Figs. 1 and 2 of the drawings, the supporting-wheel 27 is provided upon the rear face of its rim with ratchet-teeth 78, which are adapted for engagement by the pawl 20 when the supporting-wheel is rotated in one direction and to slide freely over the teeth when the wheel is rotated in the opposite direction.

The operation of the sharpener is as follows: The parts having been assembled to form the structure above described and the disk having been adjusted to the supporting-wheel 27, as illustrated, the cutting-tool 76 is brought to engage the convexed face of the disk adjacent to the rim. Referring now to Fig. 1 of the drawings, the lever 45 is swung to the right and is raised, the frictional engagement of the cutting-tool with the disk

causing the disk and the supporting-wheel to rotate slightly as the lever is raised, at which time the spring-pressed pawl will ride over the ratchet-teeth. The lever is then moved 5 downwardly and at the same time is held to press the tool tightly against the face of the disk, at which time the pawl will engage a ratchet-tooth and hold the wheel and the disk from rotating. Continued movement of the 10 lever will cause corresponding movement of the cutter, with the result that a shaving will be cut from the surface of the disk. By continuing to raise and lower the lever the disk will be adjusted for the successive cuts, and 15 the successive cuts will be made until a chip has been taken throughout the circumference of the disk. The tool may be then adjusted to take a second chip in the same plane or it may be adjusted to take a chip at an angle to 20 the plane of the first chip, after which a third chip may be taken to cut off the angular projection resulting from the first two chips, and the disk may be finished with a keen cutting edge. During this oscillation of the shaft 25 25 the roller 53 is in engagement with the inner face of the disk, and while limiting the movement of the lever laterally in one direction it permits free vertical movement of the lever.

It will of course be understood that the 30 mechanism above described may be operated in any suitable manner and for any purpose to which it is adapted and also that the specific structure and arrangement shown may be modified and that any suitable materials 35 and proportions may be used without departing from the spirit of the invention.

What is claimed is—

1. A disk-sharpener comprising a rotatable disk-support, means for holding the support 40 against rotation in one direction, and a movable tool-carrier adapted to hold a tool in operative relation to a disk upon the support, to adjust the disk in one direction and move the tool with respect to the disk in a different direction.

2. A disk-sharpener comprising a movable disk-support, means for holding the support against movement in one direction, and a tool-carrier adapted to hold a tool in operative relation to a disk upon the support and move the tool in one direction to move the support and to move the tool in an opposite direction to cut the disk.

3. A disk-sharpener comprising a movable disk-support, means for holding the disk against movement in one direction, and a tool-carrier movable into and out of operative relation to the support and adapted to hold a tool in operative relation to a disk 55 upon the support and to move the tool in different directions to move the support and to cut the disk.

4. A disk-sharpener comprising a movable disk-support provided with a ratchet, a pawl 60 adapted for engagement with the ratchet to hold the support against movement in one direction, a tool-carrier adapted to hold a

tool in operative relation to a disk on the support and to move the tool alternately in opposite directions to move the support and to 70 cut the disk, and means for moving the carrier.

5. A disk-sharpener comprising a rotatable disk-support, means for holding the support against movement in one direction, a lever 75 pivoted coaxially with the support, and a tool-carrier mounted upon the lever and adapted for movement into and out of operative relation with a disk upon the disk-support, to engage a tool with the disk, said lever being adapted for movement upon its pivot to operate the tool to alternately rotate the disk-support and cut the disk.

6. A disk-sharpener comprising a rotatable disk-support, a link rotatably mounted coaxially with the disk-support and having a friction-roller adapted for engagement with a disk upon the support, said link being adapted for movement to engage the roller with and disengage it from the disk, a lever pivoted to the 85 link, a tool-carrier adjustably mounted upon the lever and adapted for movement therewith into and out of operative relation to the disk-support, and means for holding the carrier in its adjusted positions, said carrier being adapted to hold a tool against the disk upon the support and adapted for oscillatory movement with the lever peripherally of the 90 disk.

7. A disk-sharpener comprising a rotatable 100 disk-support, means for holding the disk against rotation in one direction, a link rotatably mounted coaxially with the disk-support and having a friction-roller adapted for engagement with a disk upon the support, 105 said link being adapted for movement to engage the roller with and disengage it from the disk, a lever pivoted to the link, a tool-carrier adjustably mounted upon the lever and adapted for movement therewith into and out of 110 operative relation to the disk-support, and means for holding the carrier in its adjusted positions, said carrier being adapted to hold a tool against the disk upon the support and adapted for oscillatory movement with the 115 lever peripherally of the disk.

8. A disk-sharpener comprising a bracket 120 provided with a bearing, a disk-support having an extension rotatably mounted in the bearing, a ratchet upon the support, a spring-pressed pawl mounted in the bracket and lying in operative relation to the ratchet, a ring 125 rotatably mounted upon the bracket, a link pivoted to the ring at one end and provided with a friction-roller at the opposite end adapted for engagement with a disk upon the support, a lever pivoted to the link and movable toward and away from the disk upon the support, and a tool-carrier adjustably mounted 130 upon the lever and movable therewith into and out of operative relation to a disk to move the disk and the carrier in one direction and to cut the disk in a different direction.

9. In a disk-sharpener, the combination

with a supporting-bracket comprising a sleeve provided with a bearing, of a disk-supporting wheel having an extended hub rotatably mounted in the bearing, a bolt passed through 5 the bearing and hub, a centering-block upon the bolt and adapted to enter the central perforation of a disk and clamp the latter upon the supporting-wheel and concentric therewith, ratchet-teeth carried by the wheel, a 10 pawl mounted in the bracket in operative relation to the ratchet-teeth and adapted to hold the wheel from rotating in one direction, and

a tool-carrier pivotally mounted concentric with the wheel, said carrier being adapted to hold a tool against a disk upon the wheel and oscillate the tool peripherally of the disk to alternately move the wheel and cut a chip. 15

In testimony that I claim the foregoing as my own I have hereto affixed my signature in the presence of two witnesses.
